WINDING MACHINE

George B. Dierking, Albany, Calif., assignor of
one-half to F. D. Taft, Oakland, Calif.

Application August 24, 1932, Serial No. 630,259

1 Claim. (Cl. 242—81)

This invention relates to improvements in winding devices and has particular reference to a machine for winding wire into coils, which coils may be dropped away from the winding machine through gravity, thus saving considerable time in the handling of the coils.

A further object is to produce a device which is simple to manufacture.

A further object is to produce a device where-
in the end of the wire is firmly held during the winding operation, and which will release the wire when the coil is finished and dropped from the winding machine.

Other objects and advantages will be apparent
during the course of the following description.

In the accompanying drawings forming a part
of this specification and in which like numerals
are employed to designate like parts throughout
the same,

20 Fig. 1 is a side elevation of my device,
Fig. 2 is a top plan view of Fig. 1,
Fig. 3 is a cross sectional view taken on the
line 3—3 of Fig. 2 and looking in the direction
of the arrows,
25 Fig. 4 is an enlarged fragmentary detail view
partly in cross section showing the wire grip-
ping means, and

Fig. 5 is an enlarged detail view showing the
manner in which the two halves of the winding
30 wheel are locked in alignment with each other.

The usual method of winding wire requires con-
siderable time to take the coil off from the reel
or drum, after the coil has been completed. If
heavy wire is being wound it often requires sev-
35 eral attendants to handle the wire. Applicant
has, therefore, devised a simple winding machine
wherein when the necessary amount of wire has
been wound upon a separable drum, then the
two halves of the drum are drawn apart and
40 the coiled wire dropped between the two parts of
the drum and rolled away, either through a chute
arrangement or in any other approved manner.

In the accompanying drawings wherein for
45 the purpose of illustration is shown a preferred
embodiment of my invention, the numeral 5 des-
ignates a base having a head stock 6 and a tail
stock 7. These head and tail stocks may be
formed in any desired manner. The tail stock
6 has bearings 8 in which a shaft 9 rotates. This
50 shaft is driven through the medium of a pulley
wheel 11 and has secured to its opposite end
from the pulley wheel, one-half of a split drum
which half is designated by the numeral 12. The
tail stock 7 has bearings 13 and 15, which sup-
55 port a shaft 14, which shaft in turn carries half

of the split drum, designated by the numeral 16. The half 16 and half 12 are adapted to cooperate so as to form a complete winding drum, as illus-
trated in Fig. 2. These drums are lined up so
that a wire receiving orifice 17 is in alignment 60
with a wire engaging clamp 18. This clamp is
forced outwardly by a spring 19 and has a head
21 through the medium of which, the clamp may
be pulled against the tension of the spring 19.
The shaft 14 has a handle 22 between which han-
65 dle and the bearing 15, is positioned a spring 23.
A collar 24 is secured to the shaft 14 and when
in inoperative position, underlies a U-shaped
member 26 which U-shaped member is carried
upon a bell-crank lever 27 pivoted as at 28 to 70
the tail stock 7 and connected by a spring 29 to
the base 5. A handle 31 serves to rotate the bell-
crank lever upon its pivot and against the ten-
sion of the spring 29. A spring 30 is secured
75 to the bearing 13 and extends toward the hub
of the disc half 16, the purpose of which spring
will be later seen. Secured to the face of the
drum half 12 is a stop 32 having a recess 33 and
an inclined surface 34. Secured to the drum half
80 16 is a pin 36, the purpose of which will be later
seen.

Assuming now that the device is assembled as
shown in Figs. 1 and 2 and it is desired to wind
a coil, the operation will be as follows:

If the parts are in the position shown in Fig.
1, the operator first strikes the handle 22 a blow
in the direction of the arrow of Fig. 2. This
causes the shaft 14 and its attached parts to
move toward the left of the drawing, thus com-
pressing the spring 23 and moving the collar 24
90 out from under the U-shaped member 26 to the
position shown in Fig. 2. The spring 29 will im-
mediately function to cause the U-shaped mem-
ber to engage the shaft and to ride thereon at a
point back of the collar 24, thus preventing the
95 spring 23 from returning the parts from the posi-
tion of Fig. 2 to that of Fig. 1. We will now as-
sume that as this operation is taking place, the
pulley 11 through any desired medium, had been
100 delivering power to the shaft 9 and as a conse-
quence the drum half 12 will have been rotated,
as for instance, in a clock-wise direction viewed
from its face and consequently the cam surface
34 of the stop will have engaged the pin 36 of the
approaching drum half 16 with the result that
105 the pin 36 will ride up the cam 34 and drop into
the recess 33, at which time the two drum halves
will be together and will be rotated in unison.

Assuming that this has occurred, the operator
now stops the machine, grasps the handle 21 110

pulling the clamp 18 backward towards the tension of the spring 19, inserts the wire as shown in Fig. 4 and then again applies power to the pulley. The wire will now be wound upon the pulley until a desired amount has been reeled into a coil. If desired, tie wires may be inserted through slots such as shown at A, which will hold the coil during transportation. Assuming now that the coil has been tied, the operator presses upon the handle 31 of the bell-crank lever 28 thus moving the U-shaped member from its position in the reel of the collar 24. The spring 23 will immediately function to draw the drum portion 16 away from the drum portion 12, at which time the hub of the drum portion 16 will engage the spring 30 and thus take up the shock or jar which would otherwise be transmitted to the bearing 13. The coil now released from the two drum halves will drop to the base 5 or onto a trough or chute from which place it will be transmitted to any desired point.

It is to be understood that the form of my invention herewith shown and described is to be

taken as a preferred example of the same and that various changes relative to the material, size, shape and arrangement of parts may be resorted to without departing from the spirit of the invention or the scope of the subjoined claim.

Having thus described my invention, I claim:

In a device of the character described, a base, a head stock, a tail stock, bearings carried thereby, a shaft carried by said head stock, a drum 10 half carried by said shaft, means for rotating said shaft, a shaft carried by said tail stock, a drum half carried by said last mentioned shaft, means for moving said last mentioned drum half into engagement with said first mentioned drum half, 15 locking means for holding said drum halves in contact one with the other, said means including a collar secured to said last mentioned shaft, and a U-shaped member engaging said shaft and normally abutting one end of said collar when 20 said drum halves are in engagement one with the other.

GEORGE B. DIERKING.
